UNITED STATES PATENT OFFICE.

ALBERT A. HODGKINS, OF BRIDGEPORT, CONNECTICUT.

SHUTTLE-MOTION FOR TWO-BANK LOOMS.

1,348,417.

Specification of Letters Patent. Patented Aug. 3, 1920.

Application filed December 26, 1919. Serial No. 347,281.

To all whom it may concern:

Be it known that I, ALBERT A. HODGKINS, a citizen of the United States, residing at 141 Bronx avenue, Bridgeport, county of 5 Fairfield, State of Connecticut, have invented an Improvement in Shuttle-Motion for Two-Bank Looms, of which the following is a specification.

This invention relates to the shuttle motion of narrow ware or narrow fabric looms. 10 Looms of this character weave a series of narrow fabrics side by side, such fabrics, if desired, having different characters or colors of filling or weft, a plurality of series 15 or banks of shuttles being employed to produce this result, each series or bank carrying filler or weft threads having the desired characteristics and being brought into play as dictated by the pattern of the fabric being woven, or a plurality of fabrics may be 20 woven in vertical relation. Shuttles of each series or bank are moved across the warp space of their respective fabric to lay the filling or weft, and various means have been 25 devised to impart the desired movement to the shuttles.

The object of the present invention is to 30 simplify the shuttle motion as applied solely to two banks of shuttles. By so limiting my machine a more effective and positive movement of the shuttles is given, thereby allowing increase of speed in the shuttle motion, and the use of numerous parts and devices for obtaining the same end, which are 35 incorporated in more complicated and less limited devices for operating a plurality of banks where only two banks of shuttles are necessary, is avoided, the simple shuttle motion mechanism of the present invention requiring considerably less space than the 40 more complicated mechanism heretofore used, thus making provision for a greater number of shuttles and warp spaces than could heretofore be arranged on frames of the same length.

With the above and other objects in view 45 the invention comprises the construction, arrangement and operation of parts as now to be described and hereinafter specifically claimed.

In the drawings forming a part of this specification,

Figure 1 is a fragmentary front elevation 50 of one end of the loom showing the lay of the batten and its associated elements;

Fig. 2 a fragmentary side elevation looking from the right of Fig. 1;

Fig. 3 a detail end elevation of the batten and certain of its associated elements; and

Fig. 4 is a fragmentary perspective view 60 of one end of the batten and certain of its associated elements, parts being broken away to better show the structure.

The frame 10 may be of any usual construction suitable for supporting the operative parts, and the batten beam 11 located on the frame, carries a bracket 12 having parallel upstanding arms 13 and 14. In upstanding arm 13 is journaled a shaft 15 having fixed on its outer end duplicate grooved 70 pulleys 16, and fastened to the grooved pulleys are straps 17 and 18, strap 17 going over its pulley from right to left and strap 18 over its pulley from left to right, as shown in Fig. 1, each for three quarters of the circumference, more or less, of its pulley. On the loom frame is arranged a revoluble spindle carrying parallel cranks 19 which are connected by a stud 20. After leading over loose pulleys 21 and 22 arranged on brackets secured to the floor, the straps are attached to studs 23 and 20 carried by the upper and lower ends, respectively, of the cranks.

The batten beam is carried by lay swords 85 24 on pivot pins 25 and may be moved forward and backward by an arm 26 having suitable connection with a shaft 27 on the loom frame.

The upstanding parallel arms carry slides 90 which as shown are offset toward each other, as indicated at 28, and have outer parallel portions 29 and 30 which slidably engage arm 13, as clearly indicated at 31 and 32, respectively, and inner parallel portions 33 95 and 34 which slidably engage arm 14, as clearly indicated at 35 and 36, respectively. The inner end of shaft 15 fixedly carries a gear wheel 37 arranged to mesh with parallel portions 29 and 30, and each of parallel portions 33 and 34 is provided with a rack pin 38, the rack pins, as shown, being at opposite ends thereof. Arm 14 is provided with a downwardly extending pin 39 and an upwardly extending pin 40, each located at the position shown in Fig. 4. The purpose of pins 39 and 40 will be hereinafter explained. While I have shown and described slides of a particular configuration, it will be apparent that the slides may be 110

made in any suitable form and that the rack pins may be situated in any suitable location to operate the actuating racks.

41 is the upper and 42 the lower shuttle rail of the shuttle frame 43. The upper and lower shuttle rails are each provided with a shuttle rack, and to one end of each rack is secured a sliding shuttle rack plate, indicated at 44 and 45, respectively, and each 10 of the racks carries teeth which have engagement with small pinions in the shuttle races which actuate the shuttles. Each of the sliding shuttle rack plates is provided with openings 46 properly positioned for the entrance of pins 38, respectively, and openings 47 properly positioned for the entrance of pins 39 and 40, respectively. The shuttles 48 are vertically arranged in banks, any number to a bank, and are guided in shuttle races formed by members 49 and 50. Spaces A between the banks are each ample for the passage of the warp, the raising of the shed, and the throwing of the shuttle through the shed.

25 Connector 51 passes through the batten beam and has pivotal engagement at its upper end with a bracket secured to the base of the lower shuttle rail. At its lower end it has pivotal connection with a lever 30 52 as indicated at 53.

With each revolution of the shaft carrying the parallel cranks with the studs thereon, the straps 17 and 18 will in turn effect right and left rotary motions on grooved 35 pulleys 16, and hence on gear wheel 37, one strap pulling and the other giving, and vice versa. As will be apparent, the reverse turns of the gear wheel will impart opposite movements to the slides and cause 40 them to slide back and forth in parallel planes for fixed distances along the upstanding arms.

The lever has a reciprocatory movement imparted to it by mechanism on the frame, 45 and is arranged to hold the shuttle frame in each of its extreme upward and downward positions during one complete revolution of the shaft carrying the parallel cranks. When the shuttle frame is reciprocated to its downward position, upper rack pin 38 will enter its opening 46 in the upper shuttle rack plate, and pin 40 will enter its opening 47 in the lower shuttle rack plate. A complete revolution of the parallel cranks 50 will carry each of the slides one complete trip, back and forth. The upper shuttle rack, by reason of the engagement of upper rack pin 38 with the upper shuttle rack plate, will throw the shuttles of the upper bank across their warp spaces and back. The lower shuttle rack plate, being engaged 55 by pin 40, which is stationary, will remain at rest. When now the shuttle frame is reciprocated to its upward position, upper rack pin 38 will be removed from engage-

ment with the upper shuttle rack plate, lower rack pin 38 will enter its opening 46 in the lower shuttle rack plate, pin 40 will be removed from the lower shuttle rack plate, and pin 39 will enter its opening 47 in the upper shuttle rack plate. A complete revolution of the cranks will now, in a similar manner, actuate the shuttles of the lower bank across and back, and the upper rack will remain stationary. It will of course be understood that when the shuttle frame is in its downward position, lower rack pin 38 and pin 39 will be disengaged from their openings.

Having thus described my invention, I claim:

1. In a two bank narrow ware loom shuttle motion, a shuttle frame carrying shuttle actuating racks, means for reciprocating the shuttle frame and coöperating means for moving the actuating racks, said last mentioned means comprising a reversibly turning gear wheel and slides operated thereby, the slides each carrying a rack pin.

2. In a two bank narrow ware loom shuttle motion, a shuttle frame carrying shuttle actuating racks, means for reciprocating the shuttle frame and coöperating means for moving the actuating racks, said last mentioned means comprising slides operated by a reversibly turning gear wheel.

3. In a two bank narrow ware loom shuttle motion, a shuttle frame carrying shuttle actuating racks, means for reciprocating the shuttle frame and coöperating means for moving the actuating racks, said last mentioned means comprising a plurality of slides.

4. In a two bank narrow ware loom shuttle motion, a shuttle frame carrying shuttle actuating racks means for reciprocating the shuttle frame and coöperating means for moving the actuating racks, said last mentioned means comprising a plurality of slides each carrying a rack pin.

5. In a two bank narrow ware loom shuttle motion, a shuttle frame carrying shuttle actuating racks, means for reciprocating the shuttle frame and coöperating means for moving the actuating racks, said last mentioned means comprising a plurality of slides each carrying a fixedly located rack pin.

6. In a two bank narrow ware loom shuttle motion, a shuttle frame carrying shuttle actuating racks, means for reciprocating the shuttle frame and coöperating means for moving the actuating racks, said last mentioned means comprising a reversibly turning gear wheel and angular slides operated thereby, the angular slides each carrying a rack pin.

7. In a two bank narrow ware loom shuttle motion, a shuttle frame carrying shuttle actuating racks, means for reciprocating

the shuttle frame and coöperating means for moving the actuating racks, said last mentioned means comprising a reversibly turning gear wheel and slides operated thereby, 5 each slide having an offset portion and being provided with a rack pin.

8. In a two bank narrow ware loom shuttle motion, a shuttle frame carrying shuttle actuating racks, means for reciprocating the shuttle frame and coöperating means for moving the actuating racks, said last mentioned means comprising a gear and a pair 10 of slides each carrying a rack pin.

9. In a two bank narrow ware loom shuttle motion, a shuttle frame carrying shuttle actuating racks, means for reciprocating the shuttle frame and coöperating means for moving the shuttle actuating racks, said last mentioned means comprising a gear and a 15 pair of members arranged to slide along upstanding parallel arms, and each carrying a rack pin.

10. In a two bank narrow ware loom shuttle motion, a shuttle frame carrying shuttle actuating racks, means for reciprocating the shuttle frame, and coöperating means for actuating the shuttle racks, said last mentioned means comprising a pair of reciprocating slides each carrying a rack pin. 20

30 11. In a two bank narrow ware loom shuttle motion, a shuttle frame carrying shuttle actuating racks, means for reciprocating the shuttle frame and coöperating means for moving the shuttle actuating racks, said last mentioned means comprising slides the 35 opposite edges of which are guided by upstanding parallel arms.

12. In a two bank narrow ware loom shuttle motion, a shuttle frame carrying shuttle actuating racks, means for reciprocating the shuttle frame and coöperating means for moving the shuttle actuating racks, said last mentioned means comprising slides and a gear wheel which is adapted to 40 mesh with the slides.

13. In a two bank narrow ware loom shuttle motion, a shuttle frame carrying shuttle actuating racks, means for reciprocating the shuttle frame and coöperating means for actuating the shuttle racks, said last mentioned means comprising slides and a gear wheel which is adapted to mesh with the slides, said slides being offset toward each other and having inner parallel portions carrying rack pins, the outer and inner edges of said slides having sliding engagement, respectively, with outer and inner upstanding parallel arms. 45

14. In a two bank narrow ware loom shuttle motion, a shuttle frame carrying shuttle actuating racks, means for reciprocating the shuttle frame, and coöperating means for actuating the shuttle racks, said last mentioned means comprising slides and a gear wheel which is adapted to mesh with 50

the slides, and said slides carried by the batten beam of the loom.

15. In a two bank narrow ware loom shuttle motion, a shuttle frame carrying shuttle actuating racks, means for reciprocating the shuttle frame, and coöperating means for actuating the shuttle racks, said last mentioned means comprising slides which are carried by the batten beam of the loom. 70

16. In a two bank narrow ware loom shuttle motion, a shuttle frame carrying shuttle actuating racks, means for reciprocating the shuttle frame, and coöperating means for actuating the shuttle racks, said last mentioned means comprising slides which are carried by the batten beam of the loom and are provided with angular portions carrying rack pins. 75

17. In a two bank narrow ware loom shuttle motion, a shuttle frame carrying shuttle actuating racks, means for reciprocating the shuttle frame, and coöperating means for actuating the shuttle racks, said last mentioned means comprising angular slides which are carried by the batten beam of the loom and are provided with upwardly and downwardly extending rack pins. 80

18. In a two bank narrow ware loom shuttle motion, a shuttle frame carrying shuttle actuating racks, means for reciprocating the shuttle frame, and coöperating means for actuating the shuttle racks, said last mentioned means comprising angular slides which are arranged to mesh with a reversibly turning gear wheel and are provided with upwardly and downwardly extending rack pins. 90

19. In a two bank narrow ware loom shuttle motion, a shuttle frame carrying shuttle actuating racks, means for reciprocating the shuttle frame, and coöperating means for actuating the shuttle racks, said last mentioned means comprising slides which are provided with rack pins and which are arranged to mesh with a reversibly turning gear wheel. 100

20. In a two bank narrow ware loom shuttle motion, a shuttle frame carrying shuttle actuating racks, means for reciprocating the shuttle frame, and coöperating means for actuating the shuttle racks, said last mentioned means comprising angular slides having inner parallel portions carrying rack pins and slidably supported by the batten beam of the loom and arranged to mesh with a reversibly turning gear wheel. 110

21. In a two bank narrow ware loom shuttle motion, a shuttle frame carrying shuttle actuating racks, means for reciprocating the shuttle frame, reciprocating slides provided with rack pins for actuating the shuttle racks, and means carried by the loom adapted to alternately engage the shuttle actuating racks, whereby the shuttle 120

- racks may be alternately actuated and positively held in a stationary position.
22. In a two bank narrow ware loom shuttle motion, a shuttle frame carrying shuttle actuating racks, means for reciprocating the shuttle frame, reciprocating slides provided with rack pins for actuating the shuttle racks, and means whereby the shuttle racks may be alternately held in stationary position.
23. In a two bank narrow ware loom shuttle motion, a shuttle frame carrying shuttle actuating racks, means for reciprocating the shuttle frame, reciprocating slides provided with rack pins for alternately actuating the shuttle racks, plates carried by the shuttle racks and provided with openings, and means adapted to alternately engage each of said openings to hold said plates in stationary position.
24. In a two bank narrow ware loom shuttle motion, a shuttle frame carrying shuttle actuating racks, means for reciprocating the shuttle frame, reciprocating slides having rack pins for alternately actuating the shuttle racks, plates carried by the shuttle racks, and means alternately engaging the plates and holding them in stationary position.
- 30 25. In a two bank narrow ware loom

shuttle motion, a shuttle frame carrying shuttle actuating racks, means for reciprocating the shuttle frame, reciprocating slides having rack pins for alternately actuating the shuttle racks, plates carried by the shuttle racks, and means for alternately holding the shuttle racks in stationary position.

26. In a two bank narrow ware loom shuttle motion, a shuttle frame carrying shuttle actuating racks, means for reciprocating the shuttle frame, reciprocating slides having rack pins and adapted to mesh with a gear wheel for alternately actuating each of the shuttle racks, plates carried by the shuttle racks, and means adapted to alternately engage each of said plates to hold the shuttle racks in stationary position.

27. In a two bank narrow ware loom shuttle motion, a shuttle frame carrying shuttle actuating racks, means for reciprocating the shuttle frame, slides having rack pins and adapted to mesh with a gear wheel for alternately actuating each of the shuttle racks, a shaft by which the gear wheel is carried, means for reversibly turning said shaft, and means for alternately engaging each of said shuttle racks whereby they may be held in stationary position.

In testimony whereof I affix my signature.

ALBERT A. HODGKINS.
